UNITED STATES PATENT OFFICE.

LEONARD L. DAVIS, OF SPRINGFIELD, MASSACHUSETTS.

DESIGN FOR AN ELECTRIC-LAMP BULB.

SPECIFICATION forming part of Design No. 30,856, dated May 23, 1899.

Application filed April 8, 1899. Serial No. 712,326. Term of patent 7 years.

To all whom it may concern:

Be it known that I, LEONARD L. DAVIS, a citizen of the United States of America, and a resident of Springfield, in the county of Hampden and State of Massachusetts, have invented and produced a new and original Design for an Electric-Lamp Bulb, of which the following is a full, clear, and exact description.

This design relates to the peculiar and distinctive formation or contour of the glass bulb for an incandescent electric lamp; and the design consists in certain modifications of or departures from the ordinary pear shape in which electric-lamp bulbs are commonly formed, whereby the bulb is rendered of an extremely pleasing shape.

The leading characteristic of the design consists in an annular shoulder or bead at an intermediate part of the neck of the lamp-bulb, having a rounded outer edge and joined to the adjacent intermediate portions of the neck of the lamp-bulb thereabove by a concave surface continuation, A in the drawing representing the bulb, B representing the shank portion, which is of substantially cylindrical

form, merging into the approximately spherical upper part *a* of the bulb in divergent curves, and *b* representing the encircling shoulder or bead formed at the intermediate part of the shank of the lamp, the rounded salient portion of which merges into the portion of the shank next thereabove by the concave curving surfaces, as indicated at *d*, and the upper portion of the bulb is formed with its top carried to the apex in lines external of a true spherical contour, and as indicated at *ff*, being a departure from the primary ball-shaped top and also a departure from the very common central upstanding sharply-tapering teat heretofore comprised in the formation of the bulbs.

What I claim is—

The design for an electric-lamp bulb substantially as herein shown and described. 45

In testimony whereof I have signed my name in presence of two subscribing witnesses.

LEONARD L. DAVIS.
